DESIGN FOR AN EYE TESTING INSTRUMENT

Raymond F. E. Stegeman, Rochester, N. Y., assignor to Bausch & Lomb Optical Company, Rochester, N. Y., a corporation of New York

Application February 27, 1942, Serial No. 106,009

Term of patent 14 years

To all whom it may concern:

Be it known that I, Raymond F. E. Stegeman, a citizen of the United States and a resident of Rochester, county of Monroe, and State of New York, have invented a new, original, and ornamental Design for an Eye Testing Instrument, of which the following is a specification, reference being had to the accompanying drawing, forming a part thereof.

Fig. 1 is a front view of an eye testing instrument showing my new design.

Fig. 2 is a side view thereof.

Fig. 3 is a top plan view thereof.

The characteristic features of the design are shown in full lines on the drawing.

I claim:

The ornamental design for an eye testing instrument, substantially as shown and described.

RAYMOND F. E. STEGEMAN.
